UNITED STATES PATENT OFFICE.

GEORGE E. MILLER, OF BOSTON, MASSACHUSETTS, ASSIGNOR TO THE CARTER'S INK COMPANY, OF CAMBRIDGE, MASSACHUSETTS, A CORPORATION OF MASSACHUSETTS.

PASTE-JAR.

1,186,115.

Specification of Letters Patent. Patented June 6, 1916.

Application filed August 20, 1915. Serial No. 46,474.

To all whom it may concern:

Be it known that I, GEORGE E. MILLER, of Boston, in the county of Suffolk and State of Massachusetts, a citizen of the United States, have invented a new and useful Improvement in Paste-Jars, of which the following is a full, clear, and exact description, reference being had to the accompanying drawings, forming a part of this specification, in explaining its nature.

The present invention relates to a jar for containing paste or other adhesives, and pertains essentially to an improved means for closing the jar both in the original package during transportation when the jar requires a tight seal and also after the jar has been opened and during its use.

As will later be more fully explained the jar is initially closed by what will herein-after be referred to as a primary cover and also by a secondary cover or cap. The primary cover is one carried by the brush, the handle of which extends through this cover, and is adapted to rest loosely upon the open top end of the jar covering it during the continuing use of the jar and the paste within it. In the original package, however, and during transportation this primary cover forms a seal between the top open end of the jar and the secondary cover or cap which connects with the jar in such manner as to bind the primary cover tight against the top open end thereof securely sealing it.

The invention pertains to further details of construction in functional operation including the sealing of the joint between the brush and primary cover and one which permits also of the brush being moved relatively to the cover so that it may extend to any determinate distance into the body of the jar depending upon the amount of paste therein.

Other details of construction and operation will also be referred to, all of which can best be seen and understood by reference to the drawings in which—

Figure 1 shows the jar in side elevation. Fig. 2 is a vertical section of the jar, the brush which forms practically a part of the jar in that it assists in its closure, being shown in elevation. Fig. 3 is a side elevation of the secondary cover or cap. Fig. 4 is a side elevation of the brush and primary cover carried by it.

Referring to the drawings:—1 represents the body of the jar. This body is provided with an upwardly-extending, annular neck portion 2 which envelopes the opening 3 into the chamber 4 of the jar. The neck 2 is provided on the outside with threads 5 by which the secondary cover may be secured to the body of the jar as will later be explained.

6 is illustrative of the paste within the jar, and 7 represents the brush having a handle 8. Carried by the handle of the brush and resting upon the upper edge of the neck 2 of the jar and covering the opening therein is the primary cover 10. The handle 8 of the brush extends through this cover. The cover consists simply of an annular plate of sheet metal and is secured to the handle in the following manner: On the under side of the primary cover is a dished plate 11 having outwardly-extending flanges 12 around which the edge of the cover is turned, thereby securing the dished plate 11 to the cover. The plate 11 forms with the cover a small annular chamber containing cork, rubber or the like 13 through which the handle of the brush extends with a tight fit suitable to seal the opening through the cover from the chamber of the jar though permitting of the handle of the brush being moved relatively to the cover. In this connection it is to be observed that the brush, when the primary cover is in place, hangs vertically and extends down into the chamber of the jar. The union above described effected between the cover or rather the cork 13 and the handle permits of any desired adjustable positioning of the brush within the chamber of the jar and the maintenance of the brush in such adjusted position. The part 11 depending from the under side of the primary cover forms also a protuberance or boss, acting to center the cover over the open end of the jar. The depending part 11 is less in diameter than the opening through the neck of the jar and this part extends downwardly for a short distance into this opening and accordingly operates to center the cover over the open end of the jar.

Fitting over the primary cover is a cap or secondary cover 15. This cover consists of an annular, flange-forming portion 16 depending from the outer edge of which is an annular threaded rim 17 and rising from 110

the center of which is a hollow extension 18. Upon the application of this cap or secondary cover to the jar the threaded rim 17 of the cap will turn onto the neck of the jar 5 drawing the flange-forming portion of the cap into engagement with the primary cover with the upwardly-extending end of the brush inclosed within the extension 18 of the cap. When the flanged portion 16 of the 10 cap is drawn into engagement with the cover it forces the same hard against the upper edge of the neck of the jar, thereby securely sealing the opening into the jar. For making the joint more secure a fibrous washer 15 20 is preferably interposed between the primary cover and the top edge of the annular neck of the jar. This washer is made of any fibrous or other suitable material and fits around the annular dished portion 11 20 of the cover.

The cap or secondary cover 15 is applied at the time of the initial packaging of the paste and during transportation, which accordingly insures a substantially perfect 25 sealing of the paste at such time. During the use of the paste this cover is intended to be dispensed with and the jar closed by the primary cover 10, which either with or without the washer 20 affords a sufficient 30 covering for the jar during the use of the paste inasmuch as the jar remains at all times in an upright position. The portion

11 of the cover operating as a centering device as above described, enables the primary cover to always fit properly over the opening into the jar even though the brush be carelessly returned to the jar. When it is desired to more securely seal the jar this may be done simply by the application to it of the secondary cover. 35 40

Having thus fully described my invention, I claim and desire to secure by Letters Patent of the United States:—

In a paste jar, the combination comprising the body of the jar having an opening into it, a primary cover for said opening, a brush having a handle extending through said cover, a casing attached to said cover and located on the under side thereof to depend therefrom into said opening, said casing having a filling of cork or other material through which the handle of said brush extends, a washer arranged upon said casing and interposed between said cover and the top edge of the jar around the opening in it, and a secondary cover attachable to the body of the jar to have a drawing engagement with said primary cover upon the application of said secondary cover to the jar. 45 50 55
